STAND FOR DISPLAYING AND MERCHANTISING GOLF BALLS

Grant W. Tigner, 250 Fairfield St., Rosemere,
Quebec, Canada

Filed Apr. 29, 1960, Ser. No. 60,361

Term of patent 7 years

(Cl. D80—10)

Fig. 1

I claim

The ornamental design for a stand for displaying and merchandising golf balls, as shown.
